UNITED STATES PATENT OFFICE.

EDWARD P. SARGENT, OF MERRIMAC, MASSACHUSETTS.

GATE FOR CARS.

SPECIFICATION forming part of Letters Patent No. 643,986, dated February 20, 1900.

Application filed August 14, 1899. Serial No. 727,186. (No model.)

To all whom it may concern:

Be it known that I, EDWARD P. SARGENT, a citizen of the United States, residing at Merrimac, in the county of Essex and State of Massachusetts, have invented new and useful Improvements in Gates for Cars, of which the following is a specification.

My invention relates to gates for cars for preventing passengers from occupying the front platform, and is principally designed for use in connection with street-cars, although it may be employed with advantage in all descriptions of passenger-cars.

The object of the invention is to provide a swinging sectional gate one section of which is pivotally connected with the car, while the other is slidably connected with said hinged section and provided with catches to hold it in a fixed condition when the gate is closed and also with a spring-catch to hold the gate back against the front of the car when not in use.

The invention consists in the novel construction and combination of parts herein-after fully described and claimed.

In the accompanying drawings, Figure 1 is a perspective view of a portion of a car provided with my improved gate, the latter being shown closed. Fig. 2 is a detail view showing the gate open and held by the spring-catch and lug. Fig. 3 is a detail perspective view showing the catches for holding the gate closed.

In the said drawings the reference-numeral 1 designates the platform of a street or other passenger car, 2 the roof thereof, and 3 the front.

The numeral 4 designates a vertical rod secured to the platform and roof, at the front thereof, at each side of the car. Secured to the said platform and to the front 3 at each side is a vertical pintle 5, which passes through the rear end 6 of the pivoted or hinged section of the gate. This section is rectangular in form and comprises vertical bars 7 and top and bottom horizontal bars 8.

Passing through the front and intermediate bars 7 are rods 10 of the slidable section of the gate, provided at the rear or inner ends with nuts 12 to limit the outward movement thereof. The front or outer ends of these

rods are secured to a vertical bar 13, provided with a spring-latch 14, having a projection 15, which engages with a recessed or notched lug or catch 16, secured to the bar 4. There is a recessed or notched lug 17 at the lower end 55 of said rod 4, which also serves as a catch for the bar 13.

The numeral 18 designates an ornamental rail secured to the hinged section for opening and closing the same.

Secured to the lower end of the gate is a spring 19, which is adapted to engage a lug 20, secured to the front of the car, to hold the gate against this front when not in use.

In practice when the gate is closed the sliding section is extended and the latch 14 and the bar 13 engage, respectively, the lugs 16 and 17, and thus hold the gate closed and the sliding section in its extended position. To open the gate, the latch 14 is disengaged from 70 its lug and the gate swung backward against the car and the sliding section pushed inward, so as to clear the doorway of the car.

When not in use, the gate can be held against the front of the car by the spring 19 75 and lug 20.

Having thus fully described my invention, what I claim is—

1. In a car-gate, the combination, with a hinged section, a sliding section having an 80 end bar, and a spring-latch connected thereto, of a vertical rod having upper and lower notched catches to receive the spring-latch and the end bar of the sliding section to hold the gate closed, and a spring-catch for holding the gate open, substantially as described.

2. A gate comprising a hinged section and a movable or sliding section having an upright end bar provided with a spring-latch, combined with upper and lower notched or 90 recessed lugs adapted to receive said end bar and latch, respectively, substantially as set forth.

In testimony whereof I have hereunto set my hand in presence of two subscribing witnesses.

EDWARD P. SARGENT.
